DESIGN FOR A HEATER CABINET

George Herbster, Cleveland, Ohio

Application March 27, 1939, Serial No. 83,859

Term of patent 7 years

To all whom it may concern:

Be it known that I, George Herbster, a citizen of the United States, residing at Cleveland, in the county of Cuyahoga and State of Ohio, have invented a new, original, and ornamental Design for a Heater Cabinet, of which the following is a specification, reference being had to the accompanying drawing, forming a part thereof.

Fig. 1 is a perspective view of a heater cabinet showing my new design;

Fig. 2 is a side elevational view of said heater cabinet.

The right and left sides of the heater cabinet are the same, one only being illustrated.

I claim:

The ornamental design for a heater cabinet, substantially as shown and described.

GEORGE HERBSTER.
